CONDENSATE-REMOVING SYSTEM.

Application filed December 23, 1926. Serial No. 156,729.

Our invention relates to improvements in condensate removing systems which are particularly adapted for the removal of condensate from paper dryers, or for situations where steam is fed to a vessel under pressure from which the condensate or the steam must be withdrawn. In installations such as paper machines where a number of dryers are heated with steam from a supply header and where the condensate which will form in these dryers requires to be removed and conveyed to a hot well or other receiver, such removal is commonly effected by providing a condensate discharge pipe for each dryer, which pipe enters through the journal of the dryer and terminates close to the bottom of same. In order that condensate may flow through this pipe it is therefore necessary to produce an unbalanced pressure within the dryer sufficient to lift the water up to the height of the journal and this is commonly effected by maintaining a difference in pressure between the supply header and the discharge header to which the condensate discharge pipes of the several dryers are connected. With such an arrangement difficulties are experienced by reason of the fact that the bottom of the condensate discharge pipe of one or more of the dryers in the system will become unsealed, under which circumstances steam will flow freely through the condensate discharge pipe and will tend to balance the pressure between the supply header and the discharge header, thus stopping the flow of condensate from the remaining dryers.

Further to the foregoing, unless a considerable differential of pressure is maintained between the supply header and the discharge header, the presence of air in the condensate discharge pipe will stop the flow of condensate from the respective dryer to which this pipe is connected. Difficulty is also experienced as a result of the presence of air in the steam as entering the dryer. This air which accumulates immediately above the surface of the condensate reduces the thermal capacity of the dryer and has not means of egress until such time as the condensate discharge pipe becomes unsealed. In addition to the foregoing it has been found desirable to maintain a certain graduation in dryer temperatures from one end of the machine to the other and this is extremely difficult to accomplish with the differential system as above outlined by

reason of the variation in thermal conditions 55 already described.

Furthermore, the passage of steam through the various condensate discharge pipes necessitates from the point of view of economy, the use of steam separators and traps and the re-circulation of the steam so collected, and with the differential system above described it is also usually necessary to provide high pressure traps or pumps in order to supply sufficient pressure to deliver the condensate to 60 the hot well.

The objects of the present invention are to provide means whereby the above objections may be eliminated and the thermal capacity of each dryer maintained constant which capacity may be regulated so as to permit of any graduation in temperature desired. The invention also provides for the removal of the condensate as it accumulates, without permitting the passage of steam and the discharging 70 of this condensate direct to the hot well, thus eliminating the necessity for using separators, traps, or pumps. Provision is also made for the removal of air from the dryers as soon as it accumulates. 80

The invention consists essentially of an auxiliary condensate discharge pipe having one end disposed at the line of high condensate level in the dryer or vessel, a main condensate discharge pipe having its inlet disposed at a level in the dryer or vessel below that of the end of the auxiliary condensate discharge pipe, a valve therefor and means as condensate is caused to flow through the auxiliary condensate discharge pipe for actuating the valve in order to discharge the surplus condensate from the dryer, as will be more fully described in the following specification, in which:—

Fig. 1 is a sectional view of the invention. 95

Fig. 2 is a sectional view of a modification.

In the drawings like characters of reference indicate corresponding parts in each figure.

While the present invention is shown as 100 applied to a paper machine dryer roll, it will be obvious that the system may be applied to any device where pressure is admitted and a liquid accumulated and has to be removed at intervals or to a desired low level.

The numeral 1 indicates generally a paper machine dryer rotatably mounted and having a hollow shaft 2 at one end which is suitably

journalled. The numeral 3 indicates a fitting suitably supported and having a steam tight connection 4 with the end of the shaft 2. The fitting 3 is provided with a steam delivery pipe 5 extending into the dryer 1 which is in communication with a steam header 6. Extending through the steam delivery pipe 5 is a condensate discharge pipe 7, the inner end of which is downwardly curved within the 5 dryer and terminates adjacent to the inner periphery of the dryer at a level as indicated by dotted line 8 lower than the level of the bottom of the auxiliary condensate discharge pipe hereinafter referred to. The outer end 10 of the condensate discharge pipe communicates through the fitting 3 and a pipe 9 to a valve 10 having a balance weight 11 or other suitable closing means secured to one extended portion of its stem 12, tending to close 15 the valve while the opposite extended portion of the stem is adapted to be engaged by a pressurestat control to be hereinafter described. The outlet from the valve 10 communicates with a condensate discharge header 13 which may serve to receive the condensate from other dryers and which is preferably carried through to a suitable hot well 20 and back to the boilers of the plant.

The numeral 14 indicates the auxiliary condensate discharge pipe which extends through the major portion of the discharge pipe 7, passing through its wall at any suitable point as at 15, and extending downwards within the dryer 1 presents its open inner end 30 16 at the high level line 17 of the condensate. The pipe 14 extends outwards through the fitting 3 and through a choke coil 18 or any other suitable device for limiting the quantity of steam therethrough. The outer end of 35 the choke coil is connected to a pipe 19 which communicates at one end with a pressurestat 20 provided with a diaphragm 21 having a central button 22 upon which the lower extremity of the valve stem 12 is adapted to rest. 40 Communicating also with the choke coil 18 is an upstanding leg 23 which is preferably mounted in a vertical chamber 24 having a vent 25 at its upper extremity, and an outlet 26 adjacent its lower extremity which communicates with an auxiliary condensate discharge header 27. While we have shown the vertical leg 23 enclosed within a vertical chamber, it will be obvious that we may adopt 45 any other preferred construction which will prevent syphonic action taking place.

In the modification shown in Figure 2 the condensate discharge valve, indicated by the numeral 28, is of the piston type actuated by a pressure differential and is provided with a 50 stem 29 having a poppet 30 at its lower end which is adapted to open to or close against communication with the condensate discharge header 13. The upper end of the stem 29 is provided with a piston 31 endwise movable in 55 a cylinder open to the valve body 28 and hav-

ing an outlet 32 from which a pipe 33 extends. The piston 31 is provided with an orifice 34 of lesser sectional area than the pipe 33 and its associated valves.

The numeral 35 indicates a bolt for limiting the upward movement of the piston 31 and the opening movement of the poppet 30. The numeral 36 indicates a pressurestat connected to the outer end of the pipe 14 and having an outlet communicating with an open ended choke coil 37 having a smaller discharge capacity than the pipe. The diaphragm 38 of the pressurestat 36 is connected by a rod 39 with the diaphragm 40 of a further pressurestat 41 which is in communication through a pipe 42 with the steam header 6. The outlet pipe 33 leads to a pilot valve 43 having a discharge connection 44 and a poppet 45 with a stem 46 projecting downwards through the valve body and bearing adjacent one end upon a suitably fulcrumed arm as at 47, the opposite end of the arm is operably connected to the rod 39 by a fork 48. The numeral 49 indicates a weight slidably mounted upon the arm for the purpose of adjusting the operation of the valve 43.

Having thus described the several parts of our invention we will now briefly explain its function, first having reference to the invention as shown in Figure 1.

Assuming the machine to have been standing with the steam supply shut off. On the admission of steam to the dryer 1 condensation will commence and will continue until it reaches the inlet end 16 of the pipe 14. During this accumulation period, steam and such air as may have accumulated in the dryer, will flow through the pipe 14, the choke coil 18 and the leg 23, passing thence to the header 27. When the condensate has reached the high level line 17, condensate is forced through the pipe 14, the choke coil 18 and, accumulating in the leg 23, develops an increase in pressure in the pressurestat 20 which distorts the diaphragm 21 and opens the condensate discharge valve 10, thus permitting the condensate to discharge directly through the condensate pipe 9 and the valve 10 and into the condensate header 13. As soon as sufficient condensate has been discharged to again uncover the inlet end 16 of the pipe 14, steam will again flow therethrough and through the choke coil, when it will force the accumulated condensate from the leg 23, thereby reducing the pressure on the pressurestat 20 so that the weight 11 will close the valve 10, thus completing the cycle of operation.

In the modification shown in Figure 2, steam and air will flow through the pipe 14 and the choke coil 37, until the condensate level is raised to the level of the inlet end 16 of the pipe, when condensate will flow therethrough, building up a hydrostatic pressure on the diaphragm 38 of the pressurestat 36,

thus producing an unbalanced condition as between the pipes 14 and 42, and their pressurestats 36 and 41, which will move the arm 47 to open the pilot valve 43, thus relieving the pressure above the piston 31 of the condensate valve 28, permitting it to be raised by the pressure within the dryer, and the valve to be opened to discharge the condensate therefrom. As the condensate level in the dryer recedes, due to discharge through the valve 28, the pipe 14 is again caused to pass steam, which discharges the accumulated water therein through the choke coil 37, so that the pressure between the pipe 14 and the pipe 42 again becomes equalized, allowing the arm 47 to rock back to normal position, the pilot valve 43 to close and pressure to become equalized on both sides of the piston 31, so that it may descend to close the valve 28 against the continued discharge of condensate therethrough.

While we have described our invention as being actuated with one or more devices functioning under the influence of hydrostatic pressure built up by reason of flow of condensate through the auxiliary condensate discharge pipe, it will be obvious that such an increase in pressure could be built up and the system could be caused to function equally well by the introduction of a chamber in lieu of the leg into which the said auxiliary condensate discharge pipe would deliver and from which the steam or condensate so delivered would discharge, the difference in pressure being created by reason of the difference in friction head loss and the presence of flash steam pressure when condensate is flowing as compared with that experienced when steam is flowing. It is also obvious that the system could be caused to function equally well by connecting the said auxiliary discharge pipe to a chamber in which condensate would accumulate at times when condensate was flowing, the weight of the condensate thus accumulated being made to actuate the main discharge valve, or by electrical means wherein the closing of a circuit would be effected by the bridging of a pair of contacts with the condensate flowing through the pipe 14 or by a float operated switch or by the introduction of a device such as a thermostat actuated by the temperature differential of the steam as compared with that of the condensate flowing in the said pipe 14, and that any of the aforementioned or similar arrangements could be employed without departing from the spirit of the invention.

It will also be obvious that this same system may be equally well suited for various other installations, where a gas and a liquid are entered into a closed vessel and from which the liquid is required to be extracted from time to time as it accumulates.

What we claim as our invention is:

1. The combination of a hollow body hav-

ing a steam inlet, a normally closed main condensate outlet, a normally open auxiliary condensate outlet and means for opening the main outlet in response to an initial discharge of condensate through said auxiliary outlet. 70

2. Apparatus as recited in claim 1 in which the normally open auxiliary outlet is arranged to afford an outlet for steam and air contained in said body.

3. The combination of a hollow body having a steam inlet, a normally closed main condensate outlet, a normally open auxiliary condensate outlet through which a restricted preliminary discharge of condensate is effected when the condensate accumulates in said body 80 to a predetermined level above the main outlet and means for opening the main outlet in response to the discharge of condensate through the auxiliary outlet. 75

4. The combination of a hollow body having a steam inlet and a normally closed main condensate outlet, normally open auxiliary condensate outlet means for effecting a preliminary discharge of condensate when the latter accumulates in said body to a predetermined level above the closed outlet and means utilizing said discharge to effect opening of the outlet. 85

5. The combination of a hollow body having a steam inlet and upper and lower condensate outlets, the lower outlet being normally closed and the upper outlet being normally open, means for effecting an initial discharge of condensate through the upper outlet and means for automatically opening 95 the lower outlet in response to a predetermined discharge of condensate through the upper outlet. 100

6. The combination of a hollow body having a steam inlet, a normally closed main condensate outlet, a normally open auxiliary condensate outlet through which a restricted preliminary discharge of condensate is effected when the condensate accumulates in said body to a predetermined level and means 105 for periodically opening the main condensate outlet including a device adapted to be actuated by the accumulation therein of a predetermined quantity of condensate supplied through said auxiliary outlet. 110

7. The combination with a hollow body having a steam inlet and a normally closed condensate outlet of a fluid actuated device operable to open said outlet when the condensate accumulates in said body to a predetermined level above the outlet and to subsequently close said outlet before the level of the condensate is lowered to the point of unsealing the outlet, said device deriving its motive fluid from the interior of said hollow body through a normally open conduit communicating with said body at a point above the aforesaid condensate outlet. 120

8. The combination with a hollow body having a steam inlet and a normally closed 130

- condensate outlet, of fluid actuated means for periodically opening and closing said outlet, said fluid actuated means being operated to open the outlet by condensate delivered there-
5 to from said hollow body through a normally open auxiliary condensate outlet when the condensate accumulates in said body to a pre-
determined level above the closed condensate outlet and means whereby the condensate
10 outlet is subsequently closed through the agency of said fluid actuated device and before the level of condensate in said hollow body is lowered to the point of unsealing the outlet.
15 9. In combination a hollow body having a steam inlet, a normally closed main conden-

sate outlet and a normally open auxiliary discharge outlet located above the main outlet, and a fluid actuated device functioning to open the main outlet when the condensate 20 accumulates to the level of the auxiliary outlet and to subsequently close said main outlet before the level of the condensate is lowered to the point of unsealing the main outlet, said fluid actuated device communicating, via the 25 auxiliary outlet, with the interior of said hollow body and deriving its motive fluid therefrom.

Dated at Powell River, B. C., this 13th day of December, 1926.
